(57)

CLAIM

The ornamental design for a latch system, as shown and described.

DESCRIPTION

FIG. 1 is a perspective view of a latch system showing the design;

FIG. 2 is a right elevational view of the latch system of FIG. 1;

FIG. 3 is a left elevational view of the latch system of FIG. 1;

FIG. 4 is a top plan view of the latch system of FIG. 1;

FIG. 5 is a bottom plan view of the latch system of FIG. 1;

FIG. 6 is a front elevational view of the latch system of FIG. 1; and,

FIG. 7 is a rear elevational view of the latch system of FIG. 1.

In the drawings, the evenly-spaced broken lines depict portions of the article that form no part of the claimed design; the dash-dot-dash lines represent boundaries of the claimed design and form no part thereof.

1 Claim, 3 Drawing Sheets(56)
